CHRISTMAS ORNAMENT OR THE LIKE

Claude C. Freeman, Mansfield, and Robert M. Ferguson,
Irving, Tex., assignors to Container Corporation of America, Chicago, Ill., a corporation of Delaware

Filed Sept. 20, 1966, Ser. No. 3,931

Term of patent 14 years

(Cl. D29—1)

FIG. 1 is a side elevational view of a Christmas ornament or the like showing our new design; and

FIG. 2 is a top plan view of the ornament as seen from line 2—2 of FIG. 1.

The top and bottom sections are symmetrical about the longitudinal axis of the ornament.

We claim:

The ornamental design for a Christmas ornament or the like, substantially as shown and described.
